Primary Examiner — Caron D Veynar*Assistant Examiner* — Katelin G Kloberg(74) *Attorney, Agent, or Firm* — Banner & Witcoff, Ltd.(57) **CLAIM**

The ornamental design for a shoe upper, as shown and described.

DESCRIPTION

FIG. 1 is a front, right perspective view of a shoe upper, showing my new design;

FIG. 2 is a rear, left perspective view thereof;

FIG. 3 is a rear elevational view thereof;

FIG. 4 is a rear, right perspective view thereof; and,

FIG. 5 is a right side view thereof.

The broken lines immediately adjacent to the shaded area represent unclaimed boundaries of the design. The unshaded regions within or adjacent to the shaded area form no part of the claimed design. The broken lines showing the remainder of the shoe are for environmental purposes only and form no part of the claimed design.
